UNITED STATES PATENT OFFICE.

ISAAC H. MILLIKEN, OF ASPINWALL, AND WILLIAM J. REGAN, OF PITTSBURGH, PENNSYLVANIA, ASSIGNORS TO THE McCONWAY & TORLEY COMPANY, OF PITTSBURGH, PENNSYLVANIA, A CORPORATION OF PENNSYLVANIA.

UNCOUPLING MECHANISM.

1,417,544.

Specification of Letters Patent. Patented May 30, 1922.

Application filed October 6, 1921. Serial No. 505,691.

To all whom it may concern:

Be it known that we, ISAAC H. MILLIKEN and WILLIAM J. REGAN, citizens of the United States, residing, respectively, at Aspinwall, in the county of Allegheny and State of Pennsylvania, and Pittsburgh, in the county of Allegheny and State of Pennsylvania, have invented certain new and useful Improvements in Uncoupling Mechanism; and we do hereby declare the following to be a full, clear, and exact description of the invention, such as will enable others skilled in the art to which it appertains to make and use the same.

Our invention relates to uncoupling mechanism for causing the lock of a car coupler to perform an unlocking operation. While mechanism constructed in accordance with the invention is particularly well adapted for application to the Master Car Builders' standard D-type coupler having a bottom operated lock, it may also be employed with other types of couplers.

The principal object of the invention is to afford simple, compact and efficient means enabling the trainman to actuate the lock of a car coupler with comparatively small effort.

A further object of the invention is to construct such a mechanism with few simple and durable parts which may readily be assembled or disassembled and which when in cooperating relation interlock with each other so as to prevent their accidental dis-

association.

The primary feature of the invention, generally stated, consists in actuating the lock of the car coupler by means of a rotatable member which is supported rearwardly of the said lock by means adapted to swing lengthwise of the car, means movable with respect to said swinging means being provided for engaging and actuating the rotatable member.

A further feature of the invention consists in operating the lock of a car coupler by a rotatable member which is supported rearwardly of the lock by a link device capable of swinging lengthwise of the car, the said link device having means movably mounted thereon for actuating said rotatable member and affording a support for an uncoupling lever adapted to operate said means and serving to maintain the latter in assembled relation.

There are other features of the invention residing in particular combinations of parts and in details of construction, all as will hereinafter appear.

In the drawings illustrating the invention, the scope whereof is pointed out in the claims,—

Figure 1 is a view, partly in side elevation and partly in vertical section, of an uncoupling mechanism embodying the invention, the form of car coupler illustrated being the well known Master Car Builders' standard D-type.

Figure 2 is a view, partly in side elevation and partly in vertical section, of a portion of the mechanism seen in Fig. 1, the parts being shown in the positions assumed when the coupler lock has performed an unlocking movement.

Figure 3 is a detail sectional view on the line 3—3, Fig. 1.

Figure 4 is a detail sectional view on the line 4—4, Fig. 1, portions of the swinging support and of the rocking member mounted thereon for actuating the vertically rotatable member being broken away.

Figure 5 is a detail view, partly in elevation and partly in vertical central section, of the rear portion of the mechanism.

Figure 6 is a detail sectional view on the line 6—6, Fig. 1, the coupler carrier iron being omitted and portions of the coupler saddle and of the uncoupling levers being broken away.

Figure 7 is a sectional view on the line 7—7, Fig. 5.

In the drawings, 1 indicates a car coupler of the D-type. It is provided with the usual lock 2. Movable connected to the lower end of said lock and projecting downwardly therefrom through the coupler head in the usual way is a link 3 which is pivotally connected to a swinging lift lever 4 that is itself pivoted to the under side of the coupler head. The link 3 and swinging lift lever 4 shown in the drawings may be and preferably are made in conformity with the standard practice of bottom lock lift devices of the D type coupler. If the coupler is designed to have a wide range of lateral swinging movement it may be provided near the rear end of its shank with a pivot pin opening 5 adapted to receive a tail pin (not shown) whereby the coupler may be pivot-

ally connected to the draft rigging in the commonly known manner.

Movably connected to the lift lever 4 is a vertically rotatable member 6 which is 5 swingingly supported rearwardly of the lock 2 by a link device 7 through which it projects and with which it has slidable engagement. For the purpose of operatively connecting the rotatable member 6 to the 10 lift lever 4 the former is preferably provided at its forward end with a hook 8 adapted to cooperate with the eye 9 with which the member 4 is customarily formed. By means of this hook and eye connection the members 15 4 and 6 are interlockingly connected so that they may not become accidentally disassociated when the device is in service.

The swinging means 7 for supporting the vertically rotatable member 6 may conveniently be provided at its upper end with a hook 10 which is adapted to cooperate with a transversely elongated eye 11 formed on a coupler saddle 12 mounted on the coupler carrier iron 13 so as to move transversely of 20 the car when the coupler swings laterally. This affords a simple construction for permitting the supporting means 7 to swing both lengthwise and transversely of the car and to turn upon its vertical axis conformably to the various angular positions which 25 the rotatable member 6 may assume when the coupler swings sidewise. By suspending the member 7 from the transversely movable coupler saddle instead of directly connecting 30 it to the carrier iron 13, a very wide range of swinging movement of the coupler may be accommodated without causing the said member 7 to depart greatly from a vertical position.

40 The swinging supporting means 7 is preferably provided with a convex seat 14 upon which the vertically rotatable member 6 slidably bears. To afford greater ease of operation the bearing seat 14 is rounded and 45 preferably is located slightly forward of the vertical axis of the member 7 so that the member 6 retains its bearing upon the seat during an unlocking operation of the parts. The link device 7, through which the rotatable member 6 extends, preferably is provided with spaced sides 15 having apertures 16 adapted to permit the insertion and removal of the upwardly extending ends 17 of uncoupling levers 18. These uncoupling 50 levers extend towards the sides of the car and preferably are of the well known form illustrated in the I. H. Milliken Patent No. 1,184,116, dated May 23, 1916.

Movably mounted upon the swinging supporting member 7 between the sides 15 thereof is a rocking member 19 which when moved in the proper direction by either of the uncoupling levers 18 causes the member 6 to perform an unlocking rotation. The 65 member 19 is provided forwardly of its cen-

ter of rocking movement with a portion 20 which extends under and is adapted to engage the member 6, and said member 19 is also formed rearwardly of said center with a portion or shoulder 21 which extends over 70 and is adapted to engage the upper side of the said member 6. Upon an unlocking movement of the rocking member 19 its portions 20 and 21 engage opposite sides of the member 6, thereby compelling the latter to 75 perform an unlocking rotation.

The vertically rotatable member 6 extends between the spaced sides 22 of the rocking member 19 and through an opening 23 in the back of the latter, the side walls 22 preferably being spaced sufficiently far apart and the opening 23 preferably being of suitable size to permit the rotatable member 6 to angle somewhat with respect to the member 19 when the coupler swings laterally. The 80 member 19 is provided at opposite sides with apertures 24 which are in alignment with the apertures 16 of the swinging support and are adapted to receive the inner ends of the uncoupling levers 18. When the 85 uncoupling levers are in assembled relation they extend through the apertures 16 and 24 and thus serve to form an operative connection between the rocking member 19 and the swinging support 7. Below the openings 90 24 the member 19 is formed on opposite sides with rounded faces 25 which bear upon the swinging supporting link 7.

The rocking member 19 may be provided with stop lugs 26 which, by engaging the 100 respective sides 15 of the link device 7, serve to limit the rocking movement of the member 19 with respect to the link device. If desired the member 19 may also be provided with a lug or tooth 27 which, by projecting between the upper ends 17 of the uncoupling levers, assists in retaining the proper operative relation of the member 19 and the uncoupling levers.

In assembling the mechanism the hook 8 110 of the rotatable uncoupling member 6 is hooked through the eye 9 at the rear end of the pivoted lock lift lever 4. The swinging supporting member 7 is then slid over the rear end of the rotatable member 6 and is 115 turned laterally until it is at right angles to its normal position, when its hook 10 may be passed through the elongated eye 11 of the coupler saddle 12. The swinging link device 7 is then allowed to drop to normal 120 position, thus becoming interlocked with the coupler saddle 12. The rocking member 19 by which the rotatable member 6 is actuated may then be slid over the rear end of said rotatable member and seated upon the 125 swinging support 7, after which the upturned ends 17 of the uncoupling rods 18 are introduced through the openings 16 and 24 in the link device 7 and rocking member 19, respectively, and their outer ends are 130

movably supported in brackets at the sides of the car in a well known way. When so assembled the parts are interlockingly held in place.

- 5 The member 19 may be rocked with respect to the swinging link device 7 by either of the uncoupling levers 18. Upon properly manipulating either of these levers its upturned end 17 presses against the rear wall 10 of the rocking member 19 and causes the lug portions 20 and 21 of the latter to engage the vertically rotatable member 6, compelling it to perform an unlocking rotation, thereby actuating the pivoted lift lever 4 and link 3 and inducing the coupler lock 2 to perform an unlocking movement. When the uncoupling lever is released after an uncoupling movement the parts return to normal position, the rotation of the member 19 15 with respect to the swinging support 7 being limited by the stop lugs 26.

In draft and buffing movements of the coupler 1 the rotatable member 6 slides longitudinally of the car with respect to the 25 swinging link device 7 as may be necessary. During an unlocking operation the member 7 may swing lengthwise of the car to the extent which may be required to permit the forward end of the rotatable member 6 to 30 accommodate itself to the path of movement of the eye 9 of the pivoted lock lift lever 4.

We claim:

1. In an uncoupling mechanism, the combination with a car coupler and its lock, of 35 means for moving said lock to unlocked position, said means involving a member pivotally connected to said coupler, a link interposed between and movably connecting said pivoted member and said lock, a rotatable member operatively connected to said lock, means adapted to swing lengthwise of the car engaging and supporting said rotatable member rearwardly of said lock, and means movable with respect to said swinging means 40 for engaging and actuating said rotatable member.

2. In an uncoupling mechanism, the combination with a car coupler and its lock, of 45 means for moving said lock to unlocked position, said means involving a rotatable member operatively connected to said lock, swinging means slidably engaged by said rotatable member, an uncoupling lever, and means movably mounted on said swinging 50 means and adapted to be actuated by said uncoupling lever for effecting an unlocking movement of said rotatable member.

3. In an uncoupling mechanism, the combination with a car coupler and its lock, of 60 means for moving said lock to unlocked position, said means involving a rotatable member operatively connected to said lock and extending rearwardly therefrom, means adapted to swing lengthwise of the car for 65 engaging and slidably supporting said ro-

tatable member rearwardly of said lock, means carried by said swinging means and adapted to rock with respect to the latter for causing said rotatable member to perform an unlocking movement, and means for 70 actuating said rocking means.

4. In an uncoupling mechanism, the combination with a car coupler and its lock, of 75 means for moving said lock to unlocked position, said means involving a vertically rotatable member operatively connected to said lock and extending rearwardly therefrom, means adapted to swing lengthwise of the car for engaging and slidably supporting said rotatable member rearwardly of 80 said lock, a member movably mounted on said swinging means and adapted to engage the upper and lower sides of said rotatable member, and an uncoupling lever adapted to actuate said movably mounted member. 85

5. In an uncoupling mechanism, the combination with a car coupler and its lock, of 90 means for moving said lock to unlocked position, said means involving a member pivotally mounted on said coupler, a link movably connecting said pivotally mounted member to said lock, a rotatable member operatively connected to said pivotally mounted member and extending rearwardly therefrom, means adapted to swing lengthwise 95 of the car engaging and forming a support for said rotatable members, and means carried by and movable with respect to said swinging means adapted to engage and actuate said rotatable member to cause it to perform an unlocking rotation.

6. In an uncoupling mechanism, the combination with a car coupler and its lock, of 100 means for moving said lock to unlocked position, said means involving a member pivotally mounted on said coupler and operatively connected to said lock, a vertically rotatable member adapted to actuate said pivotally mounted member, swinging means engaging and forming a support for said rotatable member rearwardly of said lock, and means rotatable with respect to said swinging means engaging said vertically rotatable member for actuating the latter. 105

7. In an uncoupling mechanism, the combination with a car coupler and its lock, of 110 means for moving said lock to unlocked position, said means involving a rotatable member operatively connected to said lock, means adapted to swing lengthwise of the car affording a support for said rotatable member rearwardly of said lock, an uncoupling lever journaled on said swinging means, and means movably mounted on said swinging means adapted to be actuated by 115 said lever to cause said rotatable member to perform an unlocking movement.

8. In an uncoupling mechanism, the combination with a car coupler and its lock, of 120 means for moving said lock to unlocked position, said means involving a rotatable member operatively connected to said lock, means adapted to swing lengthwise of the car affording a support for said rotatable member rearwardly of said lock, an uncoupling lever journaled on said swinging means, and means movably mounted on said swinging means adapted to be actuated by 125 said lever to cause said rotatable member to perform an unlocking movement.

9. In an uncoupling mechanism, the combination with a car coupler and its lock, of 130 means for moving said lock to unlocked position, said means involving a rotatable member operatively connected to said lock, means adapted to swing lengthwise of the car affording a support for said rotatable member rearwardly of said lock, an uncoupling lever journaled on said swinging means, and means movably mounted on said swinging means adapted to be actuated by 135 said lever to cause said rotatable member to perform an unlocking movement.

sition, said means involving a rotatable member operatively connected to said lock, a member located rearwardly of said lock and adapted to swing lengthwise of the car, 5 a rocking device for actuating said rotatable member, said device being adapted to rock with respect to said swinging means, and an uncoupling lever adapted to actuate said rocking device, said uncoupling lever constituting means for connecting said rocking 10 device to said swinging means.

9. In an uncoupling mechanism, the combination with a car coupler and its lock, of means for moving said lock to unlocked position, said means involving a rotatable member operatively connected to said lock, a member located rearwardly of said lock and adapted to swing lengthwise of the car, means for actuating said rotatable member, 15 and a plurality of uncoupling levers each adapted to operate said actuating means, said actuating means being rotatably connected to said swinging means by said levers.

10. In an uncoupling mechanism, the combination with a car coupler, its lock and carrier iron, of means for moving said lock to unlocked position, said means involving a vertically rotatable member operatively connected to said lock and extending rearwardly therefrom, a link movably connected to said carrier iron so as to swing lengthwise of the car, a member rockingly mounted on said link and having portions between which said rotatable member extends, and a plurality of uncoupling levers adapted to actuate said rocking member to cause said rotatable member to perform an unlocking movement, said link and said rocking member having openings through which said uncoupling lever extends. 40

11. In an uncoupling mechanism, the combination with a car coupler and its lock, of means for moving said lock to unlocked position, said means involving a rotatable member operatively connected to said lock, a link located rearwardly of said lock and adapted to swing lengthwise of the car, said link having spaced sides provided with apertures, a rocking member movably disposed between the spaced sides of said link and having portions between which said rotatable member extends, and a plurality of uncoupling levers for actuating said rocking member to cause said rotatable member to 45 perform an unlocking movement, said uncoupling levers being adapted to extend through said apertures in the sides of said link and serving to maintain said rocking member in assembled relation. 55

60 12. In an uncoupling mechanism, the com-

bination with a car coupler, its lock and carrier iron, of means for moving said lock to unlocked position, said means involving a member pivotally mounted upon said coupler, means operatively connecting said pivotally mounted member to said lock, a vertically rotatable member movably connected to said pivoted member, a swinging link movably connected to said carrier iron through a hook and eye connection and having spaced 65 sides provided with apertures adapted to receive uncoupling levers, a rocking device adapted to engage and actuate said rotatable member, said rotatable member being slideable lengthwise of the car with respect to 70 said rocking device and the latter being provided with portions between which said rotatable member extends and being also provided with means for limiting the extent of its rocking movement with respect to said 75 swinging link, and a plurality of uncoupling levers extending through the apertures of 80 said swinging link and adapted to actuate said rocking device.

13. In an uncoupling mechanism, the combination with a car coupler and its lock, of means for moving said lock to unlocked position, said means involving a rotatable member operatively connected to said lock, means adapted to swing lengthwise of the car for supporting said rotatable member rearwardly of said lock, a member mounted on said swinging means so as to rock with respect thereto and adapted to engage and actuate said rotatable member, means for limiting the rocking movement of said rocking member with respect to said swinging means, and means for actuating said rocking member to cause said rotatable member to perform an unlocking movement. 100

14. In an uncoupling mechanism, the combination with a car coupler and its lock, of means for moving said lock to unlocked position, said means involving a vertically rotatable member operatively connected to said lock and extending rearwardly therefrom, means adapted to swing lengthwise of the car affording a support for said rotatable member rearwardly of said lock, said swinging means having a convex seat which is 105 slidably engaged by said rotatable member, a member rockingly mounted on said swinging means and adapted to engage and actuate said rotatable member, and means for actuating said rocking member. 110

115 In testimony whereof we affix our signatures.

ISAAC H. MILLIKEN.
WILLIAM J. REGAN.
